CLAIM

The ornamental design for a stake drive bit, as shown and described.

DESCRIPTION

FIG. 1 is a front perspective view showing my new design; FIG. 2 is a front exploded perspective view thereof; FIG. 3 is a right side view thereof; FIG. 4 is a left side view thereof; FIG. 5 is a bottom view thereof; FIG. 6 is a top view thereof; FIG. 7 is a front view thereof; FIG. 8 is a back view thereof; and, FIG. 9 is a front perspective view thereof of my new design with a hammer drill for driving a stake into the ground. The broken lines depict environmental structures and form no part of the claimed invention.
